DESIGN FOR A CASING FOR A DUPLICATING MACHINE

Edwin Jacobsen, Los Angeles, Calif.

Application May 29, 1933. Serial No. 48,242

Term of patent 14 years

To all whom it may concern:

Be it known that I, EDWIN JACOBSEN, a citizen of the United States, residing at Los Angeles, in the county of Los Angeles and State of California have invented a new, original, and ornamental Design for Casing for a Duplicating Machine, of which the following is a specification, reference being had to the accompanying drawing, forming part thereof.

Fig. 1 is a side elevation of a casing for a duplicating machine, showing my new design.

Fig. 2 is a plan view thereof.

What I claim is:

The ornamental design for a casing for a duplicating machine, as shown.

EDWIN JACOBSEN.
